(57) **CLAIM**

The ornamental design for an electronic cable, as shown and described.

DESCRIPTION

FIG. 1 is a top plan view of Embodiment 1 of an electronic cable showing my new design;

FIG. 2 is a top plan view of Embodiment 2 of an electronic cable showing my new design;

FIG. 3 is a top plan view of Embodiment 3 of an electronic cable showing my new design;

FIG. 4 is a top plan view of Embodiment 4 of an electronic cable showing my new design;

FIG. 5 is a bottom perspective view of Embodiments 1 through 4 thereof;

FIG. 6 is a bottom plan view of Embodiments 1 through 4 thereof;

FIG. 7 is another bottom plan view of FIGS. 1 through 4, which corresponds to Embodiments 5 through 8 of an electronic cable showing my new design;

FIG. 8 is another bottom plan view of FIGS. 1 through 4, which corresponds to Embodiments 9 through 12 of an electronic cable showing my new design;

FIG. 9 is another bottom plan view of FIGS. 1 through 4, which corresponds to Embodiments 13 through 16 of an electronic cable showing my new design;

FIG. 10 is another bottom plan view of FIGS. 1 through 4, which corresponds to Embodiments 17 through 20 of an electronic cable showing my new design;

FIG. 11 is another bottom plan view of FIGS. 1 through 4, which corresponds to Embodiments 21 through 24 of an electronic cable showing my new design;

FIG. 12 is another bottom plan view of FIGS. 1 through 4, which corresponds to Embodiments 25 through 28 of an electronic cable showing my new design;

FIG. 13 is another bottom plan view of FIGS. 1 through 4, which corresponds to Embodiments 29 through 32 of an electronic cable showing my new design;

FIG. 14 is another bottom plan view of FIGS. 1 through 4, which corresponds to Embodiments 33 through 36 of an electronic cable showing my new design;

FIG. 15 is another bottom plan view of FIGS. 1 through 4, which corresponds to Embodiments 37 through 40 of an electronic cable showing my new design;

FIG. 16 is another bottom plan view of FIGS. 1 through 4, which corresponds to Embodiments 41 through 44 of an electronic cable showing my new design;

FIG. 17 is a bottom perspective view of Embodiments 41 through 44 thereof;

FIG. 18 is a front elevation view of Embodiments 1 through 44 thereof; and,

(Continued)

FIG. 19 is a left side elevation view of Embodiments 1 through 44, the right side elevation view being a mirror image thereof.

In the drawing views, the even-broken line represents unclaimed portions of the electronic cable that forms no part of the claimed design. The dash-dot line represents the boundary of the claimed design.
